US0D1084904S

(12) **United States Design Patent** (10) Patent No.: **US D1,084,904 S**
(45) Date of Patent: ** Jul. 22, 2025

(54) **RING PROTECTOR**

(71) Applicant: **Jibo He**, Guangdong (CN)

(72) Inventor: **Jibo He**, Guangdong (CN)

(**) Term: **15 Years**

(21) Appl. No.: **29/989,171**

(22) Filed: **Feb. 10, 2025**

(51) LOC (15) Cl. **11-01**

(52) U.S. Cl.

USPC **D11/26**

(58) **Field of Classification Search**

USPC D11/6, 26-27, 39, 89

CPC A44C 5/00

See application file for complete search history.

(57) **CLAIM**

The ornamental design for a ring protector, as shown and described.

DESCRIPTION

FIG. 1 is a perspective view of a ring protector showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of the ring protector as it would be positioned during use.

The broken lines depict portions of the ring protector that form no part of the claimed design.

1 Claim, 9 Drawing Sheets
